H. J. GAISMAN.

METHOD OF AND DEVICE FOR DESIGNATING PHOTOGRAPHIC EXPOSURES.
APPLICATION FILED MAY 15, 1913.

1,238,506.

Patented Aug. 28, 1917.

UNITED STATES PATENT OFFICE.

HENRY J. GAISMAN, OF NEW YORK, N. Y., ASSIGNOR TO EASTMAN KODAK COMPANY,
OF ROCHESTER, NEW YORK, A CORPORATION OF NEW YORK.

METHOD OF AND DEVICE FOR DESIGNATING PHOTOGRAPHIC EXPOSURES.

1,238,506.

Specification of Letters Patent. Patented Aug. 28, 1917.

Application filed May 15, 1913. Serial No. 767,776.

To all whom it may concern:

Be it known that I, HENRY J. GAISMAN, a citizen of the United States and resident of New York city, borough of Manhattan, in the county of New York and State of New York, have invented certain new and useful Improvements in Methods of and Devices for Designating Photographic Exposures, of which the following is a specification.

10 My invention relates to improvements designed for the production of designations, such as names, dates, objects photographed, etc., upon sensitized elements, such as photographically sensitized films and the like, and 15 the object of my present invention is to enable the writing or marking of the desired designations upon an opaque protector for the sensitized element, such designation to be transferred to the sensitized element or 20 to a translucent strip or sheet located between such sensitized element and its protector, whereby after the designation has been produced, the part of the protector upon which such designation has been written or marked may readily be removed to 25 permit the light to affect the sensitized element at and adjacent to the designation upon such translucent strip.

In carrying out my invention I provide a 30 holder, preferably forming part of a camera, with means to support a sensitized element therein, said holder or camera having an opening in one wall or in its cover, and a closure for such opening, a support within 35 the holder opposed to such opening, the sensitized element being arranged between such support and opening, a preferably opaque protector or cover for the sensitized element supported within or upon the holder 40 opposed to said support and element, and a transfer material, such as a coating comprising carbon, between the protector and said element, whereby a person may, through said opening, write the desired designation 45 upon said protector and cause such designation to be transferred to said element direct or to a translucent strip or sheet between said transfer material and element, and then by suitably moving the protector from said 50 opening, such portion of said sensitized element and the designation may be exposed to light to affect the sensitized surface of said element, whereby, when the latter is developed, the designation will be fixed there- 55 on and the prints from the negative so pro-

duced will bear such designation. In order to conveniently utilize different portions of said protector, as occasion requires, I provide means for drawing said protector, as may be required, from the holder, without 60 permitting light to pass into the holder as the protector is being manipulated. In the example of my invention illustrated in the accompanying drawings I have shown a lid for the aforesaid opening provided with a 65 pair of rollers adapted to grip between them the aforesaid protector, the latter passing through a suitable opening in said lid, said rollers and opening being normally inclosed by a suitable housing or the like, whereby 70 used portions of the protector may be removed, and when a designation is to be exposed to the light said protector may be swung or moved away from the first named camera opening to expose the designation 75 and element opposed thereto.

My invention further comprises novel details of improvement and combinations of parts that will be more fully hereinafter set forth and then pointed out in the claims. 80

Reference is to be had to the accompanying drawings forming part hereof, wherein,

Figure 1 is a longitudinal sectional view of a holder constituting part of a camera embodying my invention; 85

Fig. 2 is a partly broken plan view of a portion thereof;

Fig. 3 is a section on the line 3, 3, in Fig. 2;

Fig. 4 is a section on the line 4, 4, in Fig. 2; 90

Fig. 5 is an enlarged detail of a portion of Fig. 4;

Fig. 6 is an enlarged sectional detail of the sensitized element and its protecting cover; 95

Fig. 7 is an enlarged detail of the support for the protecting cover;

Fig. 8 is a section on the line 8, 8, in Fig. 7, and

Fig. 9 is a detail of the sensitized element 100 and its parts.

Similar numerals of reference indicate corresponding parts in the several views.

In the accompanying drawings I have illustrated my improvements embodied in 105 an ordinary form of camera, comprising a casing 1 having a removable wall or cover 2, and provided with a lens 3 and bellows 4.

As my invention relates to a holder for sensitized material, it is, of course, immaterial 110

whether the bellows and lens are permanently connected to the casing or body of the holder as in the construction shown, thereby constituting what is known as a camera, or such holder is made as a separate article. The film carrying spools, 5, 6, may be supported in the holder or camera in any usual manner, by the devices 6^a, 6^b, the latter of which may be used to rotate spool 6. The film 7, carried by the spools 5, 6, is shown passing over the guides 8 and adjacent to the inner portion of cover 2 in usual manner. Cover 2 is provided with an opening 2^a opposed to the film, and within the holder opposite said opening and located along the inner surface of the film is a support 9 for the film, which may be secured to the camera in any suitable manner. The opening 2^a in cover 2 is provided with a closure or lid 10, hinged upon cover 2, as at 11, and adapted to securely close opening 2^a to prevent the admission of light therethrough except when the lid 10 is moved back. Lid 10 has an opening 10^a that is provided with a cap or cover 12, shown hinged at 13 upon lid 10. By preference, the hinges 11, 13 are spring hinges, shown provided with suitable springs 14, 15 to normally retain said lid and cap closed. The arrangement is such that when cap 12 is opened (Fig. 4), writing or marking against the film through the openings 10^a, 2^a may be effected, the support 9 retaining the film in proper position at such time. To protect the sensitized element or film 7 from the light when the cap 12 is opened, I provide a protector or protecting cover 16, shown passing between the film and cover 2. The film protector 16 is of any suitable material, such as a strip of opaque paper, between which and the film is a transfer material, shown as a coating 16^a on protector 16, adapted to be transferred, by writing or marking upon said protector, to the outer surface of the film adjacent or over the sensitized material or upon a sheet or strip 17 of translucent paper or the like located over or upon the film. It is a characteristic of the opaque paper protector 16 that it be what might be properly termed "locally deformable" when written against, so that the transfer material will be pressed against the film or strip 17 only on the lines traced by the stylus or pencil. The protector 16 is shown mounted upon a spool 18 journaled in the holder, as upon the side walls thereof, as illustrated in Fig. 7. Suitable means may be provided for retarding rotation of the spool 18, such as a spring washer 19 secured within the holder upon the side wall thereof (Figs. 7 and 8). The free end of protector 16 passes through an opening 2^b in lid 10 at any suitable distance beyond the support 9. I have shown means to prevent light from striking through the opening 2^b and also to enable protector 16 to be drawn through said opening as required. To this end I have shown a housing 20 secured upon lid 10, over opening 2^b, and within said housing a pair of rollers 21 are journaled in position to grasp protector 16 frictionally between them, so that when said rollers are rotated the protector 16 will be drawn outwardly. One or both of the rollers 21 may be provided with a finger piece 22 for rotating it. The housing 20 is shown provided with a closure or plate 23 for normally retaining the same closed against ingress of light. Said closure may be mounted in guideways 24 on housing 20 to enable the closure to be pulled out and pushed in as required.

The end portions of the sensitized element or film 7 are provided with suitable opaque strips 26 of suitable length beyond each end of the sensitized element or film, adapted to be wound upon the spools 5, 6, as usual, but the portion of said element or film that is to be used for exposure is not protected by said strip 26 (as illustrated in Fig. 6), the protector 16 that is independent of the film and its spools serving to protect the sensitized surface of said element when the part 10 or 12 is raised, yet, when the film is completely wound upon a spool one of the strips 26 will inclose the film thereon to protect the latter from light in the usual manner, and the strips 26 are of sufficient length to extend between spools 5, 6, when the film is being applied in position for use.

The exposure portion of the film between the spools may be written or marked against through the openings 10^a and 2^a when lid 12 is thrown back, as in Fig. 4, whereupon the transfer material 16^a will be transferred to the outer surface of the film, or where the translucent strip or sheet 17 is carried by or is over the film, said strip 17 will receive the markings from the transfer material 16^a.

Assume that the film is provided with the translucent strip 17 and is mounted in the holder ready for use, the protector 16 being fitted in position with its end gripped between the rollers 21, and the housing 20 closed, the lid 10 and cap 12 also being closed, as indicated in Fig. 1. Exposures through the lens may now be made in the ordinary manner without regard to producing designations upon the sensitized element. When, however, it is desired to produce a designation on said element, the cap 12 is opened and through the openings 10^a, 2^a the desired designation may be marked or written upon the protector 16 opposed to such openings, whereupon the designation will be transferred, by the transfer material 16^a, upon the translucent strip 17; but as the protector 16 is over or outward respecting the film the light will not affect the latter opposite said openings. To cause the

designation so made to be photographed upon the sensitized surface 7^a of the film, the lid 10 is thrown back, carrying with it the free end portion of protector 16, therefore by exposing to the light the portion of the film opposite the opening 2^a of cover 2, and the light will cause an effect upon the portion of the film exposed through opening 2^a in such manner that when the film is developed and printed the resulting picture or print will show a relatively light or white portion, (which I term a mortise, having thereon the designation in relatively dark lines, since the designation produced upon the translucent strip 17 acts in the nature of an image or obstruction for the passage of light to the sensitized surface. Thereupon the lid 10 and cap 12 will be closed, and exposure through the lens may be made upon the portion of the film adjacent to such designation, whereby the designation will be produced upon the resulting picture or print. It will be understood, of course, that the exposure for the picture may be made before the designation is produced on the film.

If the film be used without the translucent strip 17 the same operation should be performed, except that the transfer material 16^a from protector 16 will be transferred directly upon the film. The same effect of the light, producing a mortise and designation, will result upon the film when lid 10 and the attached end portion of protector 16 are raised, such mortise and designation appearing upon the picture printed from such negative.

To retain lid 10 closed tightly upon cover 2 I have shown the latter provided with a suitable catch 28 adapted to coact with lid 10, thereby preventing the latter from accidentally opening.

By the term "opaque" I mean a material adapted to prevent the rays of light from affecting the sensitized surface of the film, whether the protector 16 be absolutely impervious to light or of the well known ruby or other color, which, while not absolutely opaque, yet itself permits only such portion of the light to reach the film as would not photographically affect its sensitized surface.

Having now described my invention what I claim is:—

55 1. A photographic holder provided with an opening in one wall and having a support opposite said opening, an opaque protector between said opening and support, transfer material located between said support and protector adapted to be transferred to overlay the sensitized material, and means to permit exposure of a portion of a sensitized element overlaid by the transferred material through said opening.

65 2. A photographic holder provided with

an opening in one wall and having a support opposite said opening, an opaque protector between said opening and support, transfer material comprising a coating upon said opaque protector between said support and protector adapted to be transferred to overlay the sensitized material, and means to permit exposure of the overlaid portion of a sensitized element through said opening.

3. A photographic holder provided with an opening in one wall and having a support opposite said opening, an opaque protector, a translucent sheet between said protector and support, transfer material between said sheet and protector, and means to permit exposure of a portion of a film overlaid by the sheet and transferred material.

4. A photographic holder provided with an opening in one wall, and having a support opposite said opening, an opaque protector, a translucent sheet between said protector and support, transfer material between said sheet and protector, and means to permit exposure of a portion of a film overlaid by the sheet and transferred material opposed to said support, said translucent sheet and film being movable over the film support.

5. A photographic holder provided with an opening in one wall and having a support opposite said opening and to a contained sensitized element, an opaque protector overlying said element between said opening and support, transfer material between said element and protector, and means to permit exposure of the portion of said element opposite said opening.

6. A photographic holder provided with an opening in one wall, and having a support opposite said opening and a contained sensitized element, an opaque protector overlying said element between said opening and support, transfer material between said element and protector, a lid for said opening, and means to connect the free end of the protector and transfer material with said lid.

7. A photographic holder provided with an opening in one wall and having a support opposite said opening and a contained sensitized element, an opaque protector overlying said element between said opening and support, transfer material between said element and protector, means to permit exposure of the portion of said element opposed to said opening, a lid for said opening provided with an opening, and means to close the last named opening.

8. A photographic holder provided with an opening in one wall and having a support opposite said opening and a contained sensitized element, an opaque protector overlying said element between said opening and support, transfer material between

1. said element and protector, a lid for said opening provided with an opening, and means to close the last named opening, said means being carried upon said lid.
5. 9. A photographic holder provided with an opening in one wall and having a support opposite said opening and a contained sensitized element, an opaque protector overlying said element between said opening and support, transfer material between said element and protector, a lid for said opening provided with an opening, and means to close the last named opening, said means being carried upon said lid, said lid having an opening for the passage of said protector and having means to prevent the passage of light through the last named opening.
10. 10. A photographic holder provided with an opening in one wall and having a support opposite said opening and a contained sensitized element, an opaque protector overlying said element between said opening and support, transfer material between said element and protector, a lid for said opening provided with an opening, and means to close the last named opening, said means being carried upon said lid, said lid having an opening for the passage of said protector and having means to prevent the passage of light through the last named opening comprising a housing upon said lid to receive the free end of the protector.
15. 11. A photographic holder provided with an opening in one wall and having a support opposite said opening and a contained sensitized element, an opaque protector overlying said element between said opening and support, transfer material between said element and protector, a lid for said opening provided with an opening, and means to close the last named opening, said means being carried upon said lid, said lid having an opening for the passage of said protector and having means to prevent the passage of light through the last named opening, said lid or cover being provided with a pair of rollers to receive the end portion of said protector therebetween.
20. 12. A photographic holder provided with an opening in one wall and having a support opposite said opening and a contained sensitized element, an opaque protector overlying said element between said opening and support, transfer material between said element and protector, a lid for said opening provided with an opening, and means to close the last named opening, said means being carried upon said lid, said lid having an opening for the passage of said protector, said lid being provided with a pair of rollers to receive the end portion of said protector therebetween, said lid having a housing inclosing said rollers.
25. 13. A photographic holder provided with an opening in one wall, a lid to close said opening, a support opposite said opening, means to support a sensitized film to pass between said support and opening, a flexible protector covering said film passing between the film and said lid, means to connect the free end of said protector with the said lid, transfer material between said protector and film, and means upon the camera to support said protector and transfer material.
30. 14. A photographic holder provided with an opening in one wall, a lid to close said opening, a support opposite said opening, means to support a sensitized film to pass between said support and opening, a flexible protector covering said film and passing between the film and said lid, means to connect the free end of said protector with the said lid, transfer material between said protector and film, and means upon the holder to support said protector and transfer material.
35. 15. A photographic holder provided with an opening in one wall, a lid to close said opening, a support opposite said opening, means to support a sensitized film to pass between said support and opening, a flexible protector covering said film and passing between the film and said lid, means to connect the free end of said protector with the said lid, transfer material between said protector and film, and means upon the holder to support said protector and transfer material.
40. 16. A photographic holder provided with an opening in one wall, a lid to close said opening, a support opposite said opening, means to support a sensitized film to pass between said support and opening, a flexible protector covering said film and passing between the film and said lid, means to connect the free end of said protector with the said lid, transfer material between said protector and film, and means upon the holder to support said protector and transfer material.
45. 17. A photographic holder provided with a movable cover having an opening, a lid to close said opening, said lid being provided with an opening, a cap to close the last named opening, a support within the camera opposite said openings, means to support a sensitized element between said support and openings, an opaque protector be-

23. The method of producing designations upon a photographically sensitized element within a holder normally protecting said element from light, said method consisting in transferring markings formed of light 70 obstructing material from a locally deformable opaque protector so as to overlie the element, and removing the protector from over the element so as to light print the markings upon the element. 75
24. The method of printing arbitrary designations upon sensitive photographic material consisting in applying opaque markings in arbitrary characters to a translucent support while the latter is over said material 80 and the material contained in a holder normally protecting it from light, and then light printing the portion of the sensitive material adjacent the parts protected by the markings. 85
25. The method of recording arbitrary designations on a photographically sensitive element, comprising the steps of positioning a flexible non-actinic covering embodying light resisting transfer material in a light 90 excluding relation to the element, locally deforming the flexible covering to transfer light resisting material therefrom in arbitrary markings to a position over the element, removing the untransferred material 95 from its light excluding position and thereby admitting light to record the markings on the element. 100
26. The combination with a normally light excluding holder for photographic sensitive material, of means whereby light obstructing marks may be formed within the holder in rear of the sensitive material while the same is protected from light, and means for admitting light at the rear of the material to print the marks thereon. 105
27. The combination with a normally light excluding holder adapted to contain a sensitive element, of a light obstructing covering for the element adapted to transfer light resisting marks over the latter through the application of localized pressure thereon while over the sensitive element and means for separating the covering and sensitive element whereby the marks may be light 110 printed on the latter. 115
28. The combination with a normally light excluding holder adapted to contain a sensitive element and having an opening 120 in, of a covering for the element accessible while in the holder for the reception of markings to be subsequently light recorded on the sensitive element and arranged to be withdrawn from over the sensitive element through the opening in the holder. 125
29. The combination with a normally light excluding holder adapted to contain a sensitive element and having an opening 130 therein, of a covering for the element consisting of a flexible strip carrying displace-
- 5 18. A photographic holder provided with a movable cover having an opening, a lid to close said opening, said lid being provided with an opening, a cap to close the last named opening, a support within the camera opposite said openings, means to support a sensitized element between said support and openings, an opaque protector between said support and openings adapted to overlie said sensitized element, transfer material between said protector and element, and a strip of translucent material between said transfer material and said element. 10
19. A photographic holder provided with a movable cover having an opening, a lid to close said opening, said lid being provided with an opening, a cap to close the last named opening, a support within the holder opposed to said openings, means to support a sensitized element between said support and openings, an opaque protector between said support and openings adapted to overlie said sensitized element, transfer material between said protector and element and means to remove a portion of such protector through the first named opening to expose the underlying portion of said element. 15
20. A photographic holder provided with a movable cover having an opening, a lid to close said opening, said lid being provided with an opening, a cap to close the last named opening, a support within the holder opposed to said openings, means to support a sensitized element between said support and openings, an opaque protector between said support and openings adapted to overlie said sensitized element, transfer material between said protector and element, a strip of translucent material between said transfer material and said element, and means to remove a portion of said protector through the first named opening to expose the underlying portion of said element. 20
21. The method of producing designations upon a photographically sensitized element comprising forming the desired characters in light obstructing material in the form desired while overlying the rear of said element and while the latter is protected from light and subsequently light recording such markings on the element. 25
22. The method of producing designations upon a photographically sensitized element within a holder normally protecting said element from light, said method consisting in transferring markings formed of light obstructing material from a locally deformable opaque protector so as to overlie the element and subsequently light printing the markings on the element. 30

- able opaque material and partially accessible while in the holder for the transfer therefrom of markings to be subsequently light recorded on the sensitive element and arranged to be withdrawn a little at a time from over the sensitive element through the opening in the holder.
30. The combination with a normally light excluding holder adapted to contain a sensitive element and having a light opening therein, of a locally deformable covering for the element accessible while in the holder for the reception of markings, transfer material between said covering and the element adapted to form markings to be light printed on the sensitive element, said covering being movable independently of the element to present fresh surfaces to the marking instrument.
31. The combination with a normally light excluding holder adapted to contain a sensitive element, of a light obstructing covering for the element adapted for the transfer of light resisting marks to overlie the element through the application of localized pressure thereon, said holder being provided with a light opening through which the sensitive element may be directly exposed after the formation of the marks to light print the markings on the element.
32. The combination with a normally light excluding holder adapted to contain a sensitive element having an opening therein, of a light obstructing covering for the element adapted for the transfer of light resisting marks to overlie the element by the application of localized pressure on the covering applied through the said opening in the holder, said holder being also provided with a light opening through which the sensitive element may be directly exposed independently of the covering to light print on the element, the markings applied through the first named opening.
33. The combination with a normally light excluding holder for photographic sensitive material having a shuttered opening therein, of means for supporting a strip of sensitive material and a translucent covering strip wound together into a roll within the holder, said strip being adapted to receive light resisting marks, and means for feeding the two strips past the opening to light print the marks on the sensitive strip.
34. The combination with a normally light excluding holder for photographic sensitive material having a shuttered opening therein, of means for supporting a strip of sensitive material and a translucent covering strip adapted to receive light resisting marks, movable together across the opening to light print the marks on the sensitive strip and means within the holder for applying the marks to the translucent strip while in the holder.
35. The combination with a camera having a lens opening at the front and provided with an opening in the back, and adapted to contain photographic sensitive material, of a translucent support in rear of the sensitive material, adapted to receive light obstructing markings formed thereon through the opening in the back of the camera which markings may be light printed upon the sensitive material.
36. The combination with a camera having a lens opening at the front and provided with an opening in the back, and adapted to contain photographic sensitive material, of a translucent support in rear of the sensitive material for receiving marks to be light printed upon the latter, and a locally deformable opaque covering in rear of the said support accessible through the opening in the back of the camera, and transfer material between the covering and support.
37. A holder for photographically sensitized material, having an opening and a support to hold a portion of the sensitized material opposite said opening, a locally deformable normally opaque, transfer covering between said opening and sensitized material adapted to transfer marks through the application of localized pressure to a position over the sensitive material and means to effect exposure of the marked portion of the sensitized material.
38. In combination with a holder for photographically sensitive material, having a light opening therein, of a support for said sensitized material, supporting means on one side of said opening for a deformable sheet having transfer material thereon, and supporting and operating means on the opposite side of the opening for moving said sheet across the opening for the application of designating marks thereagainst.
- Signed at New York city, in the county of New York and State of New York, this 14th day of May, A. D. 1913.
